UNITED STATES PATENT OFFICE.

CLARENCE C. HEMMICK, OF CHICAGO, ILLINOIS.

SOFT COLLAR.

1,358,544.

Specification of Letters Patent. Patented Nov. 9, 1920.

Application filed May 27, 1920. Serial No. 384,580.

To all whom it may concern:

Be it known that I, CLARENCE C. HEMMICK, a citizen of the United States, residing at Chicago, in the county of Cook and State 5 of Illinois, have invented certain new and useful Improvements in Soft Collars, of which the following is a specification.

This invention relates in general to wearing apparel, and has more particular reference to soft collars, the present application being a continuation in part of my pending 10 application, Serial No. 371,184, filed April 5, 1920.

Collars of this type comprise a neck band 15 adapted to be buttoned onto the neck band of a shirt, and a folded over portion of soft material which folds down over the neck band and conceals the same from view. Since the folded over portion is made of soft 20 material, it has a tendency to wrinkle and draw up, particularly at the forward portions thereof, with the result that it fails to present the slightly and pleasing appearance desirable in collars of this character.

Various provisions have been utilized heretofore for the purpose of holding the lower 25 edge of the folded over portion down in the desired position, but buttons and button holes are not slightly and furthermore, they 30 must necessarily be so small that they can only with difficulty be buttoned, and snap fasteners, which have also been tried, are not easy to connect and they quickly become distorted and pressed out of shape in the 35 laundry so that they cannot be connected at all.

The primary object of my present invention is to provide a soft collar of the character indicated, in which novel and important 40 proved means are utilized to hold the folded over portion of the collar in the desired position so as to prevent it from wrinkling or pulling up, thus causing the collar to fit neatly and present a smooth and pleasing 45 appearance.

In order to facilitate an understanding of my invention, I have illustrated on the accompanying drawing, one preferred embodiment thereof, from an inspection of which, 50 when considered in connection with the following description, my invention and many of its attendant advantages should be readily appreciated.

Referring to the drawings:

Figure 1 is a face view of a collar embody-

ing my invention looking at the inside of the neck band, the outer flap being turned up;

Fig. 2 is a front elevation of my improved collar; and

Fig. 3 is a sectional view on the line 3—3 60 of Fig. 2.

By reference to the drawings, it will be observed that my collar comprises essentially, a neck band 4 of well known or preferred construction equipped with the usual front button holes 5 and rear button hole 6, the neck band having secured to its upper edge the folded over portion 7 of the collar, which is adapted to fold down over the outer face of the neck band and assume 70 when on the wearer, the position illustrated in Fig. 2.

In order to hold the lower edges of the folded over portion down in the desired position at the front of the collar, I provide 75 the same near the forward corners with tabs 8, adapted to be inserted upwardly between the neck band of the collar and the neck band of the shirt. These tabs may be made either integrally with the folded over portion 80 7 or attached thereto, as desired. In the form shown on the drawings, the upper edge of each tab is inserted between the plies of the turned over portion at the lower edge thereof, as indicated by reference character 85 9, where it is secured by the row of stitching which runs around the margin of the folded over portion. The tabs should possess a certain degree of stiffness in order that they may not buckle and pull out from beneath 90 the neck band of the collar, and I therefore prefer to equip each tab with a piece of stiffening material of any preferred character. In the present instance, I have illustrated a piece of celluloid 11, interposed between the 95 plies of the tab for the purpose of imparting stiffness to the tab, but obviously, other stiffening material possessing the desired requisites may be satisfactorily substituted for the celluloid herein shown for purpose 100 of illustration merely.

When the collar is to be worn, it is buttoned on in the usual manner after the neck tie has been placed in position, and then the tabs 8 are inserted upwardly between the 105 neck band 4 of the collar and the neck band 12 of the shirt (Fig. 3), so that each tab serves to hold the lower edge of the folded over portion in smooth position and prevents the same from working up or wrin- 110

kling. Furthermore, the attachment of the lower edge of the folded over portion to the neck band of the collar prevents the tie from working down and escaping from beneath the folded over portion of the collar.

It will be obvious that I have provided a collar in which the folded portion can be secured in position quickly and easily by means of the tabs, and that these tabs do not interfere in any material respect with laundrying of the collar, nor are they liable to become injured in the laundry operations. When the collar is buttoned on, both tabs will be projecting downwardly from the lower edge of the folded over portion in the position assumed by the tab at the right in Fig. 2, and either after or before the tie is tied, these tabs are simply tucked up under the neck band of the collar so that they assume the position indicated at the left in dotted lines in Fig. 2, and in full lines in Fig. 3. While I have shown the tabs as being substantially rectangular in shape, obviously they may be rounded or somewhat pointed if desired, and as previously stated, they may be attached to the folded over portion of the collar or formed integrally therewith, as preferred.

Since the invention resides primarily in the application of holding tabs to the folded over portion of a collar, it will be manifest that it may be embodied in collars which are attached to a shirt instead of being detachable therefrom, in which instance, the collar would be provided with a slit extending entirely therethrough or through one or more of the outer plies only, adapted to receive the tab which could be inserted therein. Furthermore, on long pointed collars, it might be advisable to space the tabs a short distance from the lower edge of the folded over portion instead of placing it at the extreme edge thereof, as shown.

It is believed that my invention and many

of its attendant advantages will be understood from the foregoing without further description, and it should be obvious that the structural details disclosed are capable of considerable modification without departing from the spirit of the invention, as defined in the following claims.

I claim:

1. A soft collar comprising a neck band, a folded over portion, and a plurality of stiffened tabs carried by said folded over portion in position to be inserted between the neck band of said collar and the neck band of a shirt to retain said folded over portion in position.

2. A soft collar comprising a neck band, an outer folded over portion attached thereto, and a plurality of tabs carried by said folded over portion and adapted to be engaged with said neck band after said collar has been attached to the neck band of a shirt, said tabs being sufficiently stiff to facilitate such engagement and to prevent accidental disengagement thereof from said neck band, whereby said folded over portion is retained in position.

3. A soft collar comprising a folded over portion, provided with a plurality of tabs adapted to be turned inwardly and upwardly beneath an underlying ply of fabric so as to become engaged therewith, said tabs possessing sufficient rigidity to retain them in engaged relation with said underlying ply, whereby said folded over portion is held in position.

4. A soft collar comprising a neck band, a folded over portion and a tab carried by said folded over portion, said tab being provided with a stiffening element, and being adapted to be positioned and engaged with said neck band to retain the folded over portion in position.

CLARENCE C. HEMMICK.
